UNITED STATES PATENT OFFICE.

ROBERT C. GRAY AND CHARLES E. GASSIN, OF NEW YORK, N. Y.

IMPROVEMENT IN BREAST-PUMPS.

Specification forming part of Letters Patent No. 155,720, dated October 6, 1874; application filed August 11, 1874.

To all whom it may concern:

Be it known that we, ROBERT C. GRAY and CHARLES E. GASSIN, each of the city, county, and State of New York, have jointly invented certain new and useful Improvements in Breast-Pumps; and we do hereby declare the following to be a full, clear, and exact description of the invention, such as will enable others skilled in the art to which it pertains to make and use it, reference being had to the accompanying drawing, which forms part of this specification.

Our invention relates to an improved breast-pump, combining with a flexible tube and removable air-chamber a removable cap or diaphragm, for imparting suction to a tubular flexible rubber cushion for the nipple, substantially as hereinafter set forth and claimed.

In the drawing is represented a view of our invention in section.

A is a metallic tube, provided with valves A¹ and A², the valve A¹ opening toward the rubber diaphragm B, and the valve A² opening toward the port a'. B is a rubber cap or diaphragm, resting upon the flange A⁵ of the tube A, and inclosing beneath it the space B'. A³ and A⁴ are suitable screw-caps, for inclosing the valves and holding them in position. C is a flexible tube, united at one end to the metallic tube A, and at the other to the exit-port D¹ from the chamber E. D² is a tube extending well down into the air-chamber E from the nipple-piece D. D³ is a flexible rubber tubular cushion, sprung over the edges of the metallic nipple-piece D, so as to prevent the cold edges of the metallic nipple-piece from coming in contact with the breast. E is an air-chamber, which is readily inserted into or removed from the nipple-piece D by means of a screw-thread upon its neck. At the same time that it acts as an air-exhaust chamber, it serves to collect the milk drawn from the breast.

It is readily seen that, by removing the rubber cushion D³, the nipple-piece D can be thoroughly cleansed; and the same is also true of the rubber diaphragm B, the said diaphragm merely resting upon the flange A⁵.

The operation of the device is as follows: The nipple having been inserted into the tube of the flexible cushion D³, the air is exhausted from the chamber B' by passing two fingers

beneath the flange A⁵, and pressing with the thumb upon the diaphragm B. The valve A¹ is thereby closed, the valve A² is opened, and the air escapes. Upon releasing the thumb, the diaphragm B again expands to its original shape, the valve A² closes, A¹ opens, and the air is exhausted from the exhaust-chamber E, thus producing a suction, to draw the milk from the breast into the said chamber E. By repeating the operation, the suction is kept up until a sufficient amount is withdrawn, when an equilibrium is at once established by removing the cup-piece B, and the whole device taken apart, as set forth, and cleansed.

What we claim as new, and desire to secure by Letters Patent, is—

1. The metallic nipple-piece D, attached to the air-chamber, and separately removable therefrom, provided with the air-pipe D², exit-port D¹, and inwardly-projecting flexible shield or cushion D³, substantially as and for the purposes described.

2. In combination with the removable metallic nipple-piece D, the independent removable reservoir E, formed with a screw-thread neck or mouth, for securing it to the breast-piece, whereby said reservoir may be separately and independently removed from the nipple-piece and suction apparatus, substantially as and for the purposes described.

3. The combination of suction apparatus A B, removable nipple-piece D, independent removable reservoir E, and long flexible connection-pipe C, all constructed, arranged, and adapted to operate substantially as and for the purposes described.

4. The suction device, consisting of the rubber diaphragm B and metallic tube A, connected to the breast-piece D by a long flexible tube, C, said metallic tube A constructed with the end flanged head A⁵, for receiving the rubber diaphragm B; discharge-valve A², provided with cap A⁴; and end suction-valve A¹, provided with a cap, A³, which cap has a tubular projecting portion, which forms the connection for the flexible tube C, substantially as and for the purposes described.
